(57) **CLAIM**

The ornamental design for simple bag dispenser, as shown and described.

DESCRIPTION

FIG. 1 is a front view of a simple bag dispenser showing my new design in its assembled orientation;

FIG. 2 is a right side view thereof;

FIG. 3 is a top view thereof;

FIG. 4 is a bottom view thereof; and,

FIG. 5 is a left front isometric view thereof.

The left side view of the simple bag dispenser is a mirror image of the view shown in FIG. 2.
